US0D1085498S

(12) **United States Design Patent** (10) **Patent No.:** **US D1,085,498 S**
(45) **Date of Patent:** **** Jul. 22, 2025**

(54) **SPOTLIGHT**

(71) Applicant: **Yiwu Wenkuo E-commerce Firm, Jinhua (CN)**

(72) Inventor: **Yi Wen, Chongqing (CN)**

(73) Assignee: **Yiwu Wenkuo E-commerce Firm, Jinhua (CN)**

(**) Term: **15 Years**

(21) Appl. No.: **29/896,663**

(22) Filed: **Jul. 6, 2023**

(30) **Foreign Application Priority Data**

Jun. 2, 2023 (CN) 202330336014.0

(57) **CLAIM**

The ornamental design for a spotlight as shown and described.

DESCRIPTION

FIG. 1 is a top perspective view of a spotlight showing my new design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a right perspective view thereof.

Broken lines in the drawings depict portions of the spotlight that form no part of the claimed design.

1 Claim, 7 Drawing Sheets
